UNITED STATES PATENT OFFICE.

WILLIAM H. BROWN, OF STONINGTON, ILLINOIS.

VISE.

1,174,816.

Specification of Letters Patent.

Patented Mar. 7, 1916.

Application filed May 1, 1915. Serial No. 25,217.

To all whom it may concern:

Be it known that I, WILLIAM H. BROWN, a citizen of the United States, residing at Stonington, in the county of Christian and State of Illinois, have invented new and useful Improvements in Vises, of which the following is a specification.

The present invention relates to improvements in the construction of vises.

- 10 In carrying out my invention it is my purpose to provide a vise wherein an article may be gripped between the jaws thereof with a minimum amount of exertion upon the part of the operator.
- 15 It is also my purpose to construct a vise which will instantaneously grip or release an article wherein the pressure of the article between the jaws of the wrench will automatically force the said jaws toward 20 each other so as to more tightly engage with the said article, means comprising a lever being provided for separating the jaws to permit of the removal of the article from between the jaws of the vise.
- 25 With the above and other objects in view, the improvement resides in the construction, combination and arrangement of parts set forth in the following specification and falling within the scope of the appended 30 claims.

In the drawing: Figure 1 is a side elevation of a vise constructed in accordance with the present invention, the jaws being shown in their closed and locked position, Fig. 2 is 35 a top plan view of the same, Fig. 3 is a central longitudinal sectional view approximately on the line 3—3 of Fig. 2, Fig. 4 is a sectional view approximately on the line 4—4 of Fig. 2, Fig. 5 is a sectional view on 40 the line 5—5 of Fig. 1, Fig. 6 is a transverse vertical section approximately on the line 6—6 of Fig. 2, Fig. 7 is a vertical sectional view approximately on the line 7—7 of Fig. 1, and Fig. 8 is a vertical sectional 45 view approximately on the line 8—8 of Fig. 1.

Referring now to the drawings in detail, the numeral 1 designates the frame of my improved vise, the same including a vertical member 2 which terminates in a reduced leg 3, and the extremity of the leg may be round and threaded to receive the nut 4 should it be desired to arrange the leg in a support, or in lieu of the nut a staple or 50 the like may be employed when desired to arrange the leg upon the side of a support.

The member 2 terminates in a right angular shelf 4, and the said member or body 2 at or about its juncture with the leg 3 is formed with a right angularly extending 60 arm 5, the said arm projecting from the body 2 in an opposite direction from that in which the shelf 4 extends. The arm 5 adjacent to the body 2 and adjacent to the end of said arm is provided with suitable openings 6 and 7 respectively, and arranged within the opening 6 is the lower end of one of the members of the vise indicated by the numeral 8, while arranged within the opening 7 is the end of the second member 70 of the vise which is indicated by the numeral 9. The members 8 and 9 are pivoted in these openings as indicated by the numerals 10 and 11 respectively, and each of the members 8, 9 has its upper extremity 75 preferably widened and rounded one toward the other, providing the jaws 12 and 13 respectively and the inner or engaging faces of said jaws may be serrated so that an article may be firmly gripped between 80 the same, in a manner which will presently be described. The member 8 is provided with a threaded opening for the reception of a set screw 14, the said screw contacting with what may be termed the inner face of 85 the body 2, to limit the swinging movement of the member 8 toward the said body 2, while bearing between the rear face of the member 8 and the inner face of the body 2 are one or more spring members 15, the said 90 springs being provided to swing the member 8 upon its pivot 10 to bring its jaw 12 toward the jaw 13 of the member 9.

The shelf 4 is centrally provided with a substantially rectangular groove or channel 95 16 which is normally covered by a plate 17, and arranged within the said channel is a bar 18, the said bar passing through an opening in the member 8, below the jaw 12 thereof and also through an opening in 100 the member 9, and the end of said bar which passes through the opening in the member 9 is bifurcated, while the sides of the member 9, opposite the opening through which the said bar passes is formed or 105 otherwise provided with rearwardly extending brackets 19, each of said brackets having a longitudinally arranged elongated opening 20 through which passes a pivot pin 21 that also passes through openings in 110 the bifurcated end of the bar 18, through a rounded head 22 provided upon one end

of an operating lever 23. The head 22 is eccentrically connected with the pivot 21, and the brackets 19 are provided with spaced rollers 24 and 25 which contact with 5 the periphery of said head to afford a free action for the same when the cam lever is operated.

The sides of the bar received within the channel 16 are serrated, as indicated by the 10 numerals 26. The shelf 4 at its juncture with the body 2 is widened, and likewise the channel 14 at this portion of the said shelf is also widened, the closing cap conforming to the shape of the shelf provides 15 a complete cover for the said elongated portion of the channel as well as its widened outer end, and the said channel, it should be stated, communicates with the inner face of the body 2. The enlarged or widened 20 portions of the channel are indicated by the numerals 27, and arranged therein, to the opposite sides of the bar 18 are cam members 28 and 29 respectively, the same being secured to the shelf through the 25 medium of eccentrically arranged pivots 29—29, and the cam members or dogs 28 are provided with arms 30—30 which project beyond the inner face of the body 2.

The member 8, opposite the opening 30 through which the bar 18 passes is formed with lateral extensions or shoulders 31—31, the said shoulders being provided with angularly arranged openings 32—32, and the arms 30 of the dogs 28 are disposed within 35 the said openings, and when the device is in the position illustrated in Fig. 2 and the jaws closed without engaging an object therebetween, the arms are moved by contact with the angular walls of the openings 40 32 to bring the engaging surfaces of the cam shaped dogs only slightly in contact with the serrated sides 26 of the bar 18, but should an obstacle be arranged between the jaws it will be noted that the jaw 12 of 45 the vise member 8 will be moved toward the inner face of the body 2, rotating the said dogs to bring their engaging faces more tightly into contact with the sides of the bar 18, thus firmly gripping the bar and 50 sustaining an object firmly between the jaws. The inner or engaging faces of the cam-shaped dogs 28 may be serrated to provide a firm grip between the same and between the serrated sides of the bar 18.

55 In operation, the lever 23 is raised to substantially a horizontal position which movement brings its eccentrically pivoted head out of right contact with the bar 18 and the spring 15 will force the jaw 12 toward the 60 jaw 13, bringing the cam faces of the dogs 28 out of contact with the opposite sides of the bar, it being understood that the arms of said dogs will be swung away from each other through their contacting engagement 65 with the side walls of the openings or

grooves 30 in the lugs or lateral extensions 31 of the jaw. The jaw 13 may be swung outwardly of the jaw 12 permitting the article to be operated upon to be arranged between the said jaws. After the article is so 70 arranged the jaw 13 is forced toward the jaw 12 and into contact with the said article, which movement swings the member 8 rearwardly against the pressure of the spring, causing the arms 30 of the dogs 28 to be 75 moved outwardly, forcing the engaging faces of said dogs into contact with the sides of the bar. Thereafter, the handle 23 is swung to a downward position, slightly drawing the bar outwardly of the member 80 9, but bringing the same into tight frictional engagement with the cam faces of the dogs 28 and thus effectively retaining the article between the jaws. As it is impossible for the member 29 to be swung farther outwardly or bring its jaw away from the article between the jaws, any operation upon the article which will tend to spread the jaws will as a consequence force the jaw 12 inwardly toward the shelf, and any movement in this direction, will, it will be noted, tend to swing the arms outwardly and bring the cams into tighter frictional engagement with the sides of the bar. The set screw 14 permits of the adjusting of the jaw of the 95 member 8 so that the vise may be readily regulated to have its jaws properly engage with articles of various sizes.

From the above description, taken in connection with the accompanying drawings, 100 the simplicity of the device, as well as the advantages thereof will, it is thought, be perfectly apparent to those skilled in the art to which such invention appertains without further detailed description.

Having thus described the invention, what I claim is:

1. In a vise, two pivoted members having their free ends provided with jaws, of a bar passing through openings in the said members, pivoted dogs having cam faces adapted to co-act with the sides of the bar, said dogs being provided with arms, one of the jaws having lateral extensions formed with angular openings to receive the arms of the 110 dogs and to swing the dogs into contacting engagement with the bar when the said jaw member is moved toward the jaws, the other jaw being provided with spaced ears, and a lever having a rounded head eccentrically pivoted to the ears and connected with the bar, as and for the purpose set forth.

2. In a vise, two spaced pivoted members provided with co-acting jaws, one of said members being provided with ears disposed to the sides of its opening, the said ears being provided with elongated slots, a pivot passing through the slots and connecting the bar, a lever having a rounded head eccentrically connected with the pivot, spring 125 130

means upon the second jaw member for normally forcing its jaw toward the jaw of the first mentioned member, an adjustable element upon said second jaw member for limiting the movement in an outward direction of the said member from the first mentioned jaw member, the sides of the bar being serrated, and pivoted dogs having serrated cam surfaces disposed to the opposite sides of the 10 bar, said dogs each being provided with an extending arm, the second mentioned jaw having a laterally extending member pro-

vided with angularly arranged slots to receive the arms of said dogs whereby the movement of the first mentioned jaw toward 15 the dogs will rotate the said dogs to bring their engaging faces into contact with the serrated sides of the bar.

In testimony whereof I affix my signature in presence of two witnesses.

WILLIAM H. BROWN.
